UNITED STATES PATENT OFFICE

106,550

DESIGN FOR A SEWING MACHINE

John M. Washburn, West Hartford, Conn., assignor to The Merrow Machine Company, Hartford, Conn., a corporation of Connecticut

Application December 17, 1936, Serial No. 66,600

Term of patent 14 years

To all whom it may concern:

Be it known that I, John M. Washburn, a citizen of the United States, residing at West Hartford, in the county of Hartford and State of Connecticut, have invented a new, original, and ornamental Design for Sewing Machines, of which the following is a specification, reference being had to the accompanying drawings, forming part thereof.

Figure 1 is a front elevational view of a sewing machine, showing my new design.

Fig. 2 is a right end elevation of the sewing machine illustrated in Fig. 1.

The present design comprises as the principal

and dominating features thereof the symmetrical arrangement of the lubricant reservoir, lubricant sight feed, and the thread-tensioning devices in combination with the machine frame as shown, wherein said devices are disposed at opposite sides of said reservoir longitudinally of the frame, with the reservoir and lubricant sight feed located centrally of the frame, as viewed from the front thereof, and constituting the uppermost portion of the machine.

I claim:

The ornamental design for a sewing machine, substantially as shown and described.

JOHN M. WASHBURN.
